DESIGN FOR A VALVE

Lewis E. Smith, Dallas, Tex.

Application March 5, 1943, Serial No. 109,670

Term of patent 14 years

To all whom it may concern:

Be it known that I, Lewis E. Smith, a citizen of the United States, residing at Dallas, in the county of Dallas and State of Texas, have invented a new, original, and ornamental Design for a Valve, of which the following is a specification, reference being had to the accompanying drawing, forming part thereof.

Figure 1 is an elevational view of a valve showing my new design.

Figure 2 is a perspective view thereof, and Figure 3 is a bottom plan view.

I claim:
The ornamental design for a valve, as shown.

LEWIS E. SMITH.
